UNITED STATES PATENT OFFICE

OSCAR ALVISTUR, OF OAKLAND, CALIFORNIA

AIRPLANE-LANDING SPEED-RETARDING DEVICE

Application filed October 10, 1928. Serial No. 311,627.

The invention forming the subject matter of this application relates to devices for retarding the landing speed of airplanes, and particularly to collapsible propellers movable in an active position to resist the flight of the airplane before landing.

The landing speed of airplanes is usually extremely high, which renders the landing both uncertain and dangerous, both to bystanders on the field and to the occupants 10 of the airplane.

The primary object of my invention is the provision of a device which resists the advancement of the airplane, said device being actuated by the air current flowing past the airplane in flight, and said device being adapted to be held in an inoperative position during the normal flight of the airplane.

Another object of the invention is the provision of collapsible propellers disposed in coacting relation to the wings of an airplane and adapted to be opened at will, so as to be driven by the air currents produced by the tractor propeller of the airplane; said collapsible propellers being so designed as to offer resistance to the passage of said air currents, thereby creating a back pressure and effectively reducing the speed of the airplane before landing.

A still further object of the invention is the provision of collapsible propellers of the pusher type to be used in combination with the regular tractor type propeller of an airplane, said pusher type propeller being adapted to be opened at will and being so disposed as to be rotated by the air currents or wind produced by the tractor propeller, whereby the flow of said air currents and the advancement of the airplane is effectively resisted. Generators are mounted coaxially with said propellers so as to be rotated thereby, said generators being connected to landing lights, conveniently positioned on the airplane, so that in the event of night landing, the pilot, by turning a switch, may connect the current generated by said generators to the landing lights, whereby landing of the airplane at night is greatly facilitated.

Other objects of the invention are to provide a device of the character described that will be superior in point of simplicity, inexpensiveness of construction, positiveness of operation, facility and convenience in use, and general efficiency.

In this specification and the annexed drawings, the invention is illustrated in the form considered to be the best, but it is to be understood that the invention is not limited to such form because it may be embodied in other forms. It is also to be understood that in and by the claims following the description, it is desired to cover the invention in whatsoever form it may be embodied. The invention is clearly illustrated in the accompanying drawings, in which:

Figure 1 is a plan view of a biplane and the tail of the fuselage, part of the upper wings being broken away;

Figure 2 is a front elevation of the biplane, showing the retarding propellers in their open position;

Figure 3 is a fragmentary side view of the biplane, showing the arrangement of the means for holding the retarding propellers in place, and showing the control for releasing said holding means, this figure also illustrating the mounting of the generator upon the retarding propeller;

Figure 4 is a front view of a collapsible propeller;

Figure 5 is a fragmentary sectional view of the spring latches for holding the opposite halves of the collapsible propellers in a folded or collapsed position; and

Figure 6 is a top plan view of the collapsible propeller in a collapsed position, showing its relative position in connection with the generator on which it is mounted, and with the means for holding the opposite halves of the propeller in the collapsed position.

Referring to the accompanying drawings, wherein similar reference characters designate similar parts thruout, the various figures described above adequately illustrate my invention, and the following detailed description is commensurate with the above

95

100

mentioned drawings, in enabling an artisan to construct and assemble the constituent parts of the same.

In carrying out my invention, I make use of an airplane having a fuselage 6, upper wings 7, lower wings 8, a tractor propeller 9, and a landing gear 10 thereon. It is to be understood that although in the herein described embodiment of my invention, I illustrate the device in connection with a biplane, my device may be mounted and function efficiently on monoplanes or other types of airplanes.

In the biplane shown in the illustration, the upper wings 7 and the lower wings 8 are connected by means of struts 12. Adjacent to each outer end of the lower wings 8, between two adjacent struts 12, is mounted my speed retarding mechanism, denoted in its entirety by the numeral 13, which comprises cross members 14 extending between and secured to the adjacent struts 12, a generator 16 mounted on said cross members 14 substantially at the crossing point thereof, and a propeller, designated in its entirety by the numeral 17, and being mounted directly on the rotor of the generator 16. The propeller 17 is preferably of the pusher type relatively to the direction of flight of the airplane, and it has four blades 18 thereon. Each of the opposite hub portions 19 carries two of the blades 18 on each side of the propeller, the hub portions 19 being swingably secured upon a central hub portion 21 by means of suitable hinges 22. The blades 18 and the hubs 19 are so disposed that when the hubs 19 are turned around the hinges 22, so as to bring the blades 18 into parallelism with each other, the blades assume a parallel and spaced position relative to each other and the hub portions and the blades on the opposite sides of the central portion 21 are symmetrical. Around each set of blades 18 is a substantially semi-circular rim 23, each of said rims 23 forming half of a ring so that when the propellers are open, the semi-circular rims 23 extend in continuation of each other and form a balanced ring around said propellers.

When not in operation, the propellers are held in a folded position and are folded forwardly or toward the direction of flight of the airplane, as shown in the dotted line position in Figure 3. In this position, the semi-circular rims 23 are also disposed in symmetrical position. The propellers are held in the collapsed or folded position by means of spring catches 26, a spring catch being disposed on each side of the collapsed propeller so as to prevent the moving apart of the rims 23. In order to accomplish this effect, the catches engage the outside face of each rim when the rims are

folded. The spring catches are supported on a bracket 27.

Each spring catch comprises a cylinder 28 having a plunger 29 extending therethru, said plunger 29 being provided with an enlarged head 31. The cylinder 28 is provided with apertures in the opposite ends thereof so as to allow the reciprocating movement of the plunger therethru. A spring 32 is positioned within the cylinder 28, bearing against the rear wall of the cylinder and against the enlarged head 31 of the plunger, so as to press the plunger 31 in the direction of the propeller 17. The smaller end of each plunger 29 extends into a cross head 33. In order to prevent the sliding of the plunger 29 out of the cross head 33 and also to allow the employment of the cross head 33 for pulling the plunger 29 against the action of the spring 32, nuts 34 are provided at the smaller end of the plunger 29, threaded thereon, and bearing against the outside face of the cross head 33.

The plungers are operated by means of the cross head 33, and the cross head 33 is moved manually against the action of the spring 32, said movement being transmitted to the cross head 33 by means of a line 36 connecting each plunger to a control stick 37. Said line 36 is preferably of the usual cable and is properly guided on the airplane wings by means of pulleys 38.

In operation, during the normal flight of the airplane, the retarding propellers 17 are folded around the respective hinges 22 and are held in the folded position against moving apart by means of the spring catches 26. Before landing, it is desired to reduce the landing speed and offer further resistance to the flight or soaring thru the air. Therefore, the pilot pulls the control stick 37 toward the tail end of the fuselage, whereby a pull is exerted upon the line 36, moving the cross head 33 away from the cylinders 28, which in turn causes the movement of the plungers 29 and 31 into the cylinder against the action of the spring 32. After the plunger heads 31 are withdrawn so as not to obstruct the rims 23, then the action of the wind or air currents created by the tractor propeller 9 will force the opposite sections of the retarding propellers 17 apart around their hinges 22 until the same reach the fully extended position in which they are held by the air pressure exerted thereon.

In order to assure the opening of the opposite half of the retarding propellers 18, I use a compression spring 39, one end of which is secured to one of the hubs 19, and said compression spring 39 is disposed in such a manner as to bear against the other hub 19 when the propeller is in the folded position. Thus, when the catches 26 are released, the action of the compression

spring 39 tends to move the hubs 19 apart from each other, thereby assuring the turning of the propellers sufficiently far to be acted upon by the air currents and wind, by which they are opened and maintained in the open position in the manner heretofore described.

The propeller blades 18 are designed at such an angle as to form pusher propellers, and they are so disposed that the indraft of these propellers tends to occur from the direction of the tail of the plane. Therefore, they offer effective resistance to the passage of the air currents created by the tractor propeller 9 and successfully resist the flight of the airplane. The action of the air currents on the propeller blades 18 will result in the rotation of the whole propeller mechanism 17, and inasmuch as there is a tendency of indraft from the direction of the tail end of the airplane, the pusher propeller efficiently creates a pressure counter-acting part of the air pressure created by the tractor propeller 9, whereby the landing speed of the airplane is materially reduced and rendered safe. After the airplane is on the landing field, then the opposite halves of the collapsing propellers 17 are collapsed or folded in the position heretofore described and held in that position. During the turning of the opposite halves of the propellers 17 in the folded position, the stick 37 is moved again in a catch withdrawing position.

While the propellers 17 are rotated by the air currents, there is electric current created in the generators 16 in the usual manner. While the terminals of the generators may be connected to the radio set or to any other device in the airplane where electricity may be utilized, I prefer to use the electricity thus generated for the purpose of lighting the landing lights. Such landing lights are designed by the numeral 41 and are disposed on the lower face of the lower wings 8, adjacent to the opposite ends thereof. I propose to use a switch connected in series between the landing lights 41 and the generator 16 by which the landing lights 41 may be turned on at night, at will.

It will be recognized that a particularly simple and efficient device is provided for efficiently reducing the landing speed of airplanes. The device is readily controlled by the pilot thru the conventional control means, means being provided for securely holding the device into inoperative position. The device is actually opened in the operative position thereof by the action of the air currents and is so designed as to counteract the action of the tractor propeller 9. The rotation of the retarding propellers is utilized for generating electricity, by which landing lights are illuminated.

The controlling of the device is simple, and

the control means are of a unitary character, do not require any particular adjustment, and the whole device may be readily set in motion just before landing by a single movement of the control stick.

I claim:

1. A landing speed reducing device for airplanes, comprised of collapsible pusher propellers, rotatably mounted on the airplane at each side of the fuselage thereof; means for holding said propellers in a collapsed position; and releasing means for said holding means; said propellers being adapted to be unfolded and maintained in an operative position and rotated by the wind pressure thereon.

2. A landing speed reducing device for airplanes comprising a pusher propeller rotatably mounted on the airplane, a hub of the propeller being made in three sections, the side sections being turnable in a parallel position around the central section; blades symmetrically arranged on the side sections so as to be turnable in the direction of flight into inoperative position; means for holding said blades in inoperative position; means on said propellers for engagement with said holding means when the blades are turned in the direction of flight; and means for releasing at will said holding means; said blades being so arranged as to be turned away from each other and rotated by the action of air currents created by the flight.

3. A speed retarding mechanism comprising a central hub section; side hub sections on the opposite sides thereof, being turnable toward and away from each other; propeller blades on the side sections being turnable therewith; ring sections on the outside edges of said propellers forming a circular rim around the mechanism when the propeller blades are radially disposed relative to the central hub section; means for engaging said rings in the inoperative position of the blades for maintaining the mechanism inoperative; and means for releasing said engaging means at will; said propeller blades being so arranged as to be turned apart from each other and rotated by the thrust of wind currents thereon.

4. In an airplane, a plurality of speed retarding mechanisms mounted in balanced position upon the wings of the airplane; each mechanism comprising a propeller; blades on the propeller turnable in a substantially parallel position with each other; ring sections secured to the outside edge of the propeller blades so as to form a circular ring around the propeller when in operative position; means for engaging said ring sections, when the propeller blades are in inoperative position; and means releasing said engaging means at will; said propellers being so arranged as to be moved away from

each other and rotated by the action of air currents thereon.

5. In an airplane, a plurality of speed retarding mechanisms mounted in balanced position upon the wings of the airplane; each speed retarding mechanism comprising a propeller hub mounted on the wing and being rotatable in plane at an angle to the supporting surface of the airplane; hub sections on the opposite sides of the hub, turnable around the central portion of the hub in the direction of flight; a propeller blade on each turnable hub section; a half ring secured to the outside edge of the propeller; the half rings on the opposite sides of the mechanism describing a circular rim when the opposite propellers are positioned in the same plane; means engaging the outside faces of the half rings when the same are turned in a substantially parallel relation for holding the propellers in inoperative position (edgewise to the direction of flight); means to release said engaging means at will, thereby allowing the wind pressure to move the propellers apart and turn the same in operative position and to rotate the same; and a generator connected to landing lights of the airplane, and being driven by said retarding mechanism.

30. In testimony whereof I affix my signature.
OSCAR ALVISTUR.
